[57] CLAIM

The ornamental design for a containment basin, which can hold silt-collecting sock, sorbent material disc and locking sealing frame, as shown and described.

DESCRIPTION

FIG. 1 is a top, perspective view of a containment basin, which can hold silt-collecting sock, sorbent material disc and locking sealing frame, showing our new design;

FIG. 2 is a front side view thereof, the back, left and right sides appearing essentially the same;

FIG. 3 is a top view thereof shown with its top tray removed for clarity of illustration;

FIG. 4 is a top view thereof with the top tray in place;
FIG. 5 is a bottom view thereof; and,

FIG. 6 is a top, perspective view showing a second embodiment of a containment disc which can hold silt-collecting sock, sorbent material disc and locking, sealing frame, the side, top and bottom thereof appearing substantially identical to that shown in FIGS. 2, 4 and 5 except for the right angle corners of the top lip.
